UNITED STATES PATENT OFFICE

HERMAN IHLENBURG, OF PHILADELPHIA, PENNSYLVANIA, ASSIGNEE
MACKELLAR, SMITHS & JORDAN, OF SAME PLACE.

DESIGN FOR A FONT OF PRINTING-TYPE.

SPECIFICATION forming part of Design No. 12,136, dated January 18, 1881.

Application filed November 6, 1880. Term of patent 14 years.

To all whom it may concern:

Be it known that I, HERMAN IHLENBURG, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of a design for a font of printing-type intended for ornamental surroundings for printed matter.

I will now proceed to describe the various types of which the font is composed.

No. 1 is a section or cornice-piece for a border, composed of a vertical line from the upper extremity of which extends to the right a horizontal line with curved terminations. Within this outer figure is placed a smaller figure of similar formation, the space between the two figures ornamented by the shaded indented line having the heavy triangular figures between the indentations, the face of the smaller figure ornamented by a series of heavy lines. Upon the right of the smaller figure is placed a fan-like figure, a portion of the face of which is ornamented by a portion of the group of leaves and flowers placed below and to the right of this fan-like figure.

No. 2 is a section of an elliptical figure, the face of the base or smaller end of which is ornamented upon the right by the pistil-like ornaments, and the face of which is ornamented upon the right by the heavy indented line and light dots, followed by a series of heavy dots, to the left of which are placed a series of light horizontal lines, the upper ones of which are followed by the short heavy horizontal lines.

No. 3 is a branch of leaves, from which projects below upon the left the curved tendril.

No. 4 is a quadrant, the left-hand portion of which is ornamented upon its face by a series of light curved figures, the upper ends of which have the scroll-like terminations, within which are placed the heavy curved figures. Above these are placed, upon a heavy ground, a series of light triangular figures, at the bases of which are placed the small heavy figures, these surmounted by a heavy curved line, above which are placed a series of light inclined lines proceeding from a heavy triangular figure in the upper right-hand corner.

No. 5 is a square divided into four triangles, that upon the left unshaded, the other three shaded by a series of light lines. 55

No. 6 is a section of a molding ornamented upon its face by a series of light lines and the two heavy inclined lines, between which are placed a heavy dot.

No. 7 is a parallelogram, the lower portion 60 of which is shaded by a series of light horizontal lines placed below an unshaded square having a central dot. From the left of this square to the left of the figure extend the inclined lines with the open space between them, 65 the space above the upper one of these inclined lines shaded by the heavy lines, as shown, this portion of the figure (its lower half) succeeded by the upper half, similarly ornamented. 70

No. 8 is the center of the figure—an unshaded square surrounded by four trapezoids, the bases of which adjoin each other, forming a square, the left hand slightly shaded, the upper one shaded by a series of light lines, the 75 right-hand one shaded by a series of darker lines, and the lower one heavily shaded.

No. 9 is the center of the figure—an unshaded square surrounded by four trapezoids, which adjoin each other and form a square. The 80 top one is unshaded, the other three slightly shaded by light lines.

No. 10 is a circle, within which is placed a heavy circle. In the center is a small heavy circle, the face of the figure shaded by a series 85 of short curved lines, which rise above each other in separate groups and proceed from the outer side of the small heavy circle, gradually increasing in length as they approach the inner heavy circle.

No. 11 is a quadrantal figure, the larger portion of the figure upon the right ornamented upon its face by a series of unshaded petaloids surmounted by a heavy curved line, followed by a series of light curved lines, succeeded by a heavy dot in the upper left-hand corner. 90

No. 12 is quadrantal figure, the larger and lower portion of the figure ornamented upon its face by the triangular figures, as shown, 95 surmounted by a light curved line, followed by a series of heavy triangular figures, followed by a curved line surmounted by the heavy dot in the upper left-hand corner.

No. 13 is a right-angled triangle the hypotenuse of which is shaded by a light line. The figure is ornamented by a wreath which projects above the hypotenuse, within which is placed a small circle surrounded by a larger circle, the space between the two circles being ornamented by a series of rays, and within the smaller circle is placed a still smaller circle. The face of the triangle, above and below the wreath, is shaded by a series of light horizontal and vertical lines.

No. 14 is a circular figure, the face of which is ornamented by the net-like ornament, as shown. In the center of the figure is a square placed transversely and ornamented centrally, from the points of which project the short heavy lines, followed by the heavy dots.

No. 15 is a trapezium-shaped figure divided into two triangles, one ornamented upon its face by the light inclined lines, and the cruciform figure having the light dots placed above and below the horizontal line, the outer unshaded triangle having the bounding lines provided with a series of fine rays extending beyond them.

No. 16 is a quadrantal figure, the upper right-hand corner ornamented by a series of small pistils, followed by the light indented line, the spaces between the same shaded heavily, as shown, this followed by a light curved line, from which projects the light elongated indented line projected over and beyond the heavy groundwork, scalloped upon its periphery, from which, between the points of the indented line, project a series of short vertical lines with heavy dot terminations.

No. 17 is a tile-like ornament, ornamented on its face by a ring and the representation of a bird, the rest of the face shaded by a series of light lines.

No. 18 is the upper and right-hand portions of the figure, formed of two horizontal lines, one above the other, and two parallel vertical lines, the spaces between which are shaded by a series of light vertical and light horizontal lines. In the angle formed by these lines is placed, upon a heavy groundwork, a light cruciform figure, having placed within it a heavy cruciform figure. Below this is placed a triangular figure, divided centrally by the shaded line extending from the base of the heavy groundwork to the base of the triangular figure, the triangular figure shaded upon its face by groups of light lines in imitation of straw-work. Below the face of the triangular figures is placed an inclined line, the extremities of which are curved slightly to the left. Upon the right of this line, above and below, or from its upper and lower extremities, extend or run the curved lines, which meet the lines of the figure upon the right and terminate in the scrolls, as shown. The open spaces between the main lines of the figure and the triangular figure described are ornamented in the space above the triangular figure, by a horizontal line extending to the

left, when it is met by an inclined line, the angle formed by these lines being filled by the heavy lines, as shown, and the upper end of this inclined line continued downward and then horizontally to the left, and then inclined upward and across itself, and terminating in the scroll-like ornament, as shown, and in the space to the right of the triangular figure by a line extending downward to a point where it is met by an inclined line upon the right, the angle formed by these lines being filled by the heavy lines, as shown, and this inclined line continued in a horizontal direction upon the left, and then downward vertically, and then curved and crossing itself, and terminating upon the right in the scroll-like ornament. Below the line extending below the base of the triangular figure is placed centrally a section of a ring ornamented upon its face by a series of small heavy points, from the outer line of which ring extends downward a triangular figure, the base of which is arched about centrally, and the face of which is ornamented by a heavy figure, following the configuration of the outer figure. From this figure extends the heavy line terminating in a dot, followed by a spear-head-like ornament, upon each side of which heavy line is placed a heavy line expanded to form the rhomboidal ornament, upon each side of which is placed the curved line terminating in a dot.

No. 19 is a triangular-shaped figure, the upper right-hand corner ornamented by the indented line upon a heavy and light groundwork, as shown; below this, between a light and heavy line, a representation of the well-known Grecian border; directly below the Grecian border, and upon the right, the space ornamented by a Greek fret, the extreme left-hand portion of the figure ornamented by an indented line, ornamented upon its face by a series of light inclined lines, the spaces between the indentations ornamented by the light triangular figures upon a heavy groundwork.

No. 20 is a semicircular figure. The center is a heavy dot. A short distance below or beyond it is a heavy curved line. A short distance beyond this a light curved line, forming the base for a fret, with curved terminations, ornamented at intervals by a series of heavy dots rising above each other and diminishing in size, between which are placed the heavy pistil-like ornaments. Beyond this are placed the two curved lines, the space between them filled by a series of light inclined lines approaching each other more closely toward the upper end of the figure; beyond this two more curved lines, the space between them filled by the light inclined lines, and beyond this the heavy outer boundary of the figure, between which and the next curved line are a series of heavy dots at intervals, and the heavy triangular-shaped figure placed at intervals and extending from the second curved line within the boundary-line.

No. 21 is a corner-piece, the base of which is

a curved line, the left-hand boundary a vertical line, and the upper boundary a line at right angles to the left-hand boundary, extending to the right, the figure ornamented centrally by a light 5 ring crossing the curved line forming the base or right-hand boundary, above which rise the petaloids, shaded on each side by the heavy and light lines, the curved boundary also shaded by the light and heavy curved lines, and from 10 the lower portion of the ring proceed the groups of stem-bearing leaves, as shown.

No. 22 is a quadrantal figure, ornamented in the upper left-hand corner by a heavy triangular ornament, followed by a row of heavy 15 dots, and these followed by the heavy curved line inclosed between the light ones, the rest of the figure ornamented upon its face, as the Fig. 20 already described.

No. 23 is a representation of a horseshoe, 20 ornamented above by the knotted ribbon and upon each side by the flower, leaf, and tendril ornaments.

No. 24 is a quadrantal figure, the left-hand portion of the figure ornamented upon its 25 face by the lace-work shaded by a series of light lines. Below this are two curved lines, the space between shaded by a combination of light and heavy lines, the space between the lower of these curved lines and the outer line 30 of the figure ornamented by a lace-work-like ornament shaded by a series of light lines. Beyond the boundary-line of the figure proper extends a light curved line, and the space between these lines is ornamented by the heavy 35 shaded indented line.

No. 25 is a corner-piece similarly ornamented to the corner-piece shown in No. 21.

No. 26 is a representation of a folded figure, the lower left-hand portion ornamented on its 40 face by a series of heavy pistol-like ornaments; above a series of short light lines; above a series of pentagonal figures rising from a heavy line; above the pentagonal figures a heavy line, followed by a series of heavy dots 45 upon a light groundwork; above a heavy line, followed by a light one, the portion of the figure folded within that described ornamented upon its face by a series of light and heavy inclined lines and the heavy dots, as shown. 50 From the right-hand boundary of the figure extend a series of short light lines, as shown.

No. 27 is the outline of the figure, a heavy vertical line upon the left meeting a heavy horizontal line extending upon the right, the 55 right-hand termination of the horizontal line inclined downward to the left and the lower termination of the vertical line inclined upward to the right. Within this outline is placed a circle having within it centrally the 60 heavy circular body surrounded by a heavy ring, and this by a larger ring, the space between the two rings ornamented by the looped rope-work, as shown, upon a heavy ground, this surrounded by a larger ring, the space between them by a series of light inclined lines. 65 Outside of this ring is placed the lower boundary of the circle, forming, as it were, a con-

nection between the inclined lines of the main figure, the space between these ornamented by a series of heavy points. Outside 70 is placed a heavy indented line, terminating in the short inclined lines with dot terminations, and centrally ornamented by the heavy, triangular figures, outside of which, and between the indentations, a series of light dots 75 are placed, the angles of the figures above the circle and at its lower left-hand corner shaded by a series of light lines, the face further ornamented by the heavy star, as shown.

No. 28 is a corner-piece composed of a vertical line on the right extended to form a horizontal line upon the top, then connected upon the left by a heavy curved line. Above this is placed a shorter curved line, and the space between these curved lines is ornamented by 80 a fret-like ornament upon a groundwork of light lines. Within this figure are placed the concentric circles extending beyond the curved boundary of the figure upon the left. Above the outer circle, within the figure, is placed a 85 light curved line surmounted by the flower-like ornament, the space between the outer circle and this curved line shaded by a series of light lines, the circle ornamented upon its face by a series of light and heavy curved lines 90 and by a series of light star-like figures, the circle crossed about centrally by two curved lines ornamented by a series of light dots upon a heavy groundwork. From the outer circle project upon the left a series of short heavy 95 lines, and between these extend a series of longer light lines with dot terminations.

No. 29 is an idealized group of flowers, leaves, and grasses.

No. 30 is a branch of leaves, upon each side 105 of which is represented a bird.

No. 31 is a stem bearing leaves and flowers, upon which is represented a butterfly.

No. 32 is the representation of a bird-cage, within which is placed a bird.

No. 33 is the representation of a horseshoe ornamented by the flowers, as shown.

No. 34 is a representation of a branch of ferns.

No. 35 is a branch of leaves and flowers. Upon one of the leaves is represented a caterpillar, and above a bird.

No. 36 is a group of leaves and grasses. A cobweb is shown supported by the same.

No. 37 is an idealized group of leaves, grasses, ferns, tendrils, and fruit.

No. 38 is a representation of a lady's closed fan and a group of leaves, flowers, and tendrils.

No. 39 is a representation of a cockatoo upon a metal frame-work.

No. 40 is a representation of a stork.

No. 41 is a branch of leaves and flowers, upon which is resting a butterfly.

Having now described my invention, what I claim as new is—

The design for a font of printing-types, as 130 shown and described.

In presence of— HERMAN IHLENBURG.
